[57] CLAIM

The ornamental design for a confection dispenser, substantially as shown and described.

DESCRIPTION

FIG. 1 is a front elevational view of a confection dispenser showing my new design;
FIG. 2 is a rear view thereof;
FIG. 3 is a right side view thereof;
FIG. 4 is a top view thereof; and
FIG. 5 is a bottom view thereof.

The left side view of the confection dispenser is a mirror image of FIG. 3.

FIG. 1

FIG. 3
